UNITED STATES PATENT OFFICE.

WILLIAM J. KENNY, OF CICERO, ILLINOIS, ASSIGNOR TO AMERICAN CAN COMPANY, OF NEW YORK, N. Y., A CORPORATION OF NEW JERSEY.

BAIL-END-FORMING MACHINE.

1,343,267.

Specification of Letters Patent. Patented June 15, 1920.

Application filed August 18, 1917. Serial No. 187,010.

To all whom it may concern:

Be it known that I, WILLIAM J. KENNY, a citizen of the United States, residing in Cicero, in the county of Cook and State of Illinois, have invented a new and useful Improvement in Bail-End-Forming Machines, of which the following is a specification.

This invention relates in general to bail end forming machines and has more particular reference to the formation of bail ends of the general character illustrated and described in the co-pending application of James H. Doyle and myself filed August 18, 1917, Serial No. 186,873.

A principal object of my invention is the provision of a bail end forming machine for forming up the ends of the bails correctly and accurately and consisting of strong and simple parts arranged to require little power and unlikely to require frequent or costly repair or replacement.

A still further object of the invention is the provision of a machine which will operate at high speed and which will require merely the services of an unskilled attendant.

Other objects and advantages of the invention will be apparent as it is better understood from the following description when considered in connection with the accompanying drawing illustrating a preferred embodiment thereof.

On the drawing,

Figure 1 is a top plan view of a machine for forming bail ends embodying my present invention;

Fig. 2 is a section taken substantially on the line 2—2 of Fig. 1;

Fig. 3 is a section taken substantially on the line 3—3 of Fig. 1;

Figs. 4 and 5 are enlarged partial plan views showing the arrangement of the mechanism in its successive steps;

Fig. 6 is a section taken substantially on the line 6—6 of Fig. 4;

Fig. 7 is a partial section taken substantially on the line 7—7 of Fig. 5;

Fig. 8 is a section taken substantially on the line 8—8 of Fig. 4;

Fig. 9 is a section taken substantially on the line 9—9 of Fig. 5;

Fig. 10 is a perspective view of the finished bail;

Fig. 11 is a perspective view showing 55 one end of the bail partly formed;

Fig. 12 is a similar view showing the same end completely formed;

Fig. 13 is a view, similar to Fig. 11, of the other end of the bail;

Fig. 14 is a view of this latter end completely formed;

Fig. 15 is a plan view of the operating cams; and

Figs. 16 to 21 are perspective views of 65 the bail end forming blocks.

The embodiment of the invention shown on the drawing is particularly designed to produce a bail with the ends formed as shown in Fig. 10, which is substantially the 70 bail of the co-pending application to which reference has been made. Viewing this figure it will be noted that the ends of the bail 22 are looped at 23 and 24, one loop 23 being disposed substantially in the plane of the body and the other end 24 at right angles thereto. The terminal ends 25 and 26 are bent at right angles to the planes of the loops so that one end 25 is disposed at right angles to the plane of the body 80 of the bail and the other end 26 in this plane. It is intended that when the bail is assembled both loops will be disposed in the plane of the body, and this is attained by bending the loop 24 at right angles 85 about the point 27 of its connection with the body of the bail.

A machine illustrating an embodiment of the invention and shown on the drawings is adapted to operate upon the bails after 90 the body of the bail has been given its desired curvature and the ends brought to extend in the same general direction. This machine comprises a bed 31 mounted upon any suitable framework 32 and having a 95 pair of guide recesses 34 which carry the horizontal reciprocating forming dies to be later described. Extending up from the bed at each side is a bearing bracket or upright 35 in which is mounted a driving shaft 36 100 and a cam shaft 37. A pulley 38 and a pinion 39 are mounted upon the driving shaft 36, the pinion engaging a gear 41 on the shaft 37. The front of the bed is cut away at 42 to permit the partly formed bail 43 105 to be readily placed in operative position. Two guide bars 44 are disposed above and at the sides of each recess 34 and the hori-

horizontally movable dies are reciprocated between the bars 44. It will be understood that the various dies and forming members and their associated actuating instrumentalities are all timed by cams on the cam shaft to operate in synchronism upon the ends of the incompletely bail thus positioned. The bail is thrust across the two guide bars 44 which are preferably flush with the top of the bed and beneath a holding yoke 45, having two laterally extending arms 46, and carried upon the end of a lever 47 which is fulcrumed at 48 on the bed and carries at its rear end a roller 49 which engages a central cam 51 on the cam shaft. This holding lever is the first operative part of the machine to come into action after a bail is positioned and the arms 46 closed down on the ends of the bail pinning them to the table as may be seen by viewing Fig. 1.

Two operations in the present instance are performed on each bail end. Viewing Fig. 1, the end at the left is first given a loop in a horizontal plane and the extremity then bent up at right angles thereto. This loop is the loop 23 and it is formed by the conjoint action of two loop forming dies 52 and 53, these dies being shown in enlarged detail in Figs. 16 and 18. They each consist of a block of hard metal having slots 54 in either side for engagement with the guide bars 44 between which they reciprocate toward and from each other under the action of the cams. The block 52 is actuated by a cam lever 55 pivoted at 56 upon the table and having one end 57 engaging in a recess 58 in the block and the other end provided with a roller 59 taking into a cam groove 61 of cam part 62 on the cam shaft. A similar arrangement is provided to actuate the block 53. Lever 63 is pivoted at 64 upon the table and has an end 66 engaging in a recess 67 of block 53 and the other end 68 engaging in cam groove 69 of cam part 71. It will be noted by viewing Fig. 1 that cam grooves 61 and 69 are so constructed that when the cam shaft is rotated from the operator the levers 55 and 63 are mounted to bring the front ends 57 and 66 toward each other. It will be understood that the end of the bail extends between the two blocks and as the blocks approach, the loop 23 is formed. The block 52 is the female block and has a vertical extending recess 72 in its operative face into which fits a male part or projection 73 on the block 53. A groove 74 is provided in the recess 72 and into this groove the wire of the bail is pushed to form the loop by the projection 73. The block 53 carries a pin 75 adapted to enter into an appropriate recess 76 in the block 52, the purpose of which pin will be later explained.

At the same time that the loop 23 is being formed in the horizontal plane, the loop 24 at the other end of the bail is being formed

in a vertical plane and this is accomplished by a bending member 77 which is disposed above the end of the bail when it is inserted. This bending member is perhaps best shown in Fig. 21 and in its action co-operates with one of two horizontal reciprocating dies adapted to operate upon this end of the bail. This die in the present instance is numbered 78 and is illustrated in enlarged view in Fig. 19. Like the dies 52 and 53 it is provided with slotted ways 79 for engagement in the right hand guide bars 44. When in position the wire extends across the forward parts 81 and 82 of the member 79, said forward parts 81 and 82 providing a recess 83 between them. The adjacent faces of the parts 81 and 82 are provided with slots 84 to receive the sides of the loop under the action of the bending member 77. This member has an operative shoulder 85 adapted to move down between the parts 81 and 82 to give the loop bend to this end of the bail. Vertical reciprocation is imparted to the bending member 77 by a lever 86, having one end 87 engaging in the member 77, the other end carrying a roller 88 engaging in a cam groove 89 of cam part 91, it being understood that the bending member 77 slides in ways 92 in the frame of the machine.

Just prior to the action of the bending member 77 the die 78 is advanced to accurately position the wire and this is accomplished by a lever 93 pivoted at 94 on the bed and having an end 95 engaging in a slot or recess 96 of the die. The other end of the lever carries a roller 97 engaging in cam slot 98 of cam part 99.

As soon as the two loops have been formed, the two extreme ends of the bail are bent at right angles to the planes of their respective loops. That is to say, the extreme end of the bail at the left of Fig. 1 is bent up and the end of the bail at the right down into a horizontal plane forming the ends 25 and 26. The end 25 is bent up by a bending die, indicated at 101, which reciprocates in ways 102 in the frame. This die is pushed up from beneath by a lever 103 pivoted at 104 in the arm 105 extending down beneath the bed and having one end 106 engaged in a slot 107 of the bending member and the other end provided with a roller 108 mounted in cam slot 109 of cam part 111. An enlarged view of this bending member 101 is shown in Fig. 17 in which it will be noted that the forward corner of this member is given a recess 112 to fit the wire. This member comes up from below after the loop has been formed and bends up the end as may be observed by comparing Figs. 4 and 5, the pin 75 prevents the body of the loop from bending or distortion in this step of the operation. At substantially the same time the end 26 is formed by the die 78 and its companion 113 also

slidable in guideways 44, the die 113 is shown enlarged in Fig. 20 from which it will be noted that it also is provided with slots 114 for engagement with the guide bars 44.

5 The die 78 is recessed at 115 back of the position of the loop and the upper surface of the recess is provided with a bail end receiving depression 116. The die 113 carries a nose 117 adapted to slide over the projection 82 and into the recess 115 bending down the end 26 as may be seen by comparing Figs. 4 and 5. Die 113 receives its movement from lever 118 pivoted at 119 on the bed and having an arm 121 engaging in the 15 die. The other arm of the lever 118 carries a roller 123 taking into cam slot 124 of cam part 125.

The cams are so timed that these operations occur in quick succession and after 20 they are completed the holding arms are elevated to permit the finished bail to be removed and another inserted.

It is thought that the invention and many of its attendant advantages will be understood from the foregoing description, and it will be apparent that various changes may be made in the form, construction and arrangement of the parts without departing from the spirit and scope of the invention or 30 sacrificing most of its material advantages, the form hereinbefore described being merely a preferred embodiment thereof.

I claim:

1. A machine for forming bail ends, comprising in combination loop forming dies movable in the plane of the body of the bail, a loop forming die movable transversely to said plane, and end bending dies one movable at right angles to said plane and the 40 other movable in said plane.

2. A machine for forming bail ends, comprising in combination two pairs of loop forming dies arranged to operate in planes at right angles to each other, and two end bending dies one operating in one of said planes and the other operating in the other of said planes.

3. In a bail forming machine the combination of a pair of dies one of which is movable toward the other in the plane of the bail, said dies being shaped to grasp an end of the bail and produce a loop therein in the plane of the bail, a third die movable transversely to said plane and shaped to bend the 55 terminal portion of the bail transversely to said loop, a second pair of dies one of which is movable toward the other, said dies having portions which engage the bail near the end thereof at opposite sides of the said 60 plane, one of said dies being movable trans-

versely to said plane and adapted to bend said portion of the bail into a loop extending transversely to said plane, a sixth die movable parallel with said plane to bend the other terminal portion of the bail into position in said plane and toward the first mentioned end of the bail, and mechanism for actuating said dies. 65

4. A machine for forming bail ends, comprising in combination devices for clamping 70 the body of the bail near its end, a hook member adapted to engage over the end of said bail and movable to form a loop therein, and a sliding die for bending the end of said loop angularly with respect to the body 75 of the loop.

5. A machine for forming bail ends, comprising in combination a clamping device for holding the bail during the end forming, loop forming dies and end forming dies operative during the holding of said bail on one leg of the same, a second set of loop forming dies operating on the other leg of the bail at right angles to the first set, and a second end forming die operating at right 85 angles to the first end forming die.

6. A machine for forming bail ends, comprising in combination two sets of male and female reciprocating dies movable toward each other to form loops adjacent the ends 90 of the bail, the dies of one set operating at right angles to those of the other set, and subsequently acting vertically movable dies for bending the ends of said bail angularly with respect to said loops, said end bending 95 dies operating at right angles to each other.

7. A machine for forming bail ends, comprising in combination a holding device for engaging both sides of the bail near its ends, loop forming dies for forming loops in the 100 ends of the bails disposed at right angles to each other, and end forming dies for bending the ends of said bail angularly with respect to said loops.

8. A machine for forming bail ends, comprising in combination a holding device for engaging both sides of the bail near its ends, loop forming dies for forming loops in the 105 ends of the bails disposed at right angles to each other, and end forming dies for bending the ends of said bail angularly with respect to said loops, and a common cam control for said dies and said holding device.

Signed in the presence of two subscribing witnesses.
